UNITED STATES PATENT OFFICE

2,498,469

APPARATUS FOR ELIMINATING DUST
AND FUMES

Daniel H. Petty, Skokie, Ill., assignor to The Hydro-Blast Corporation, Chicago, Ill., a corporation of Illinois

Application February 27, 1946, Serial No. 650,653

5 Claims. (Cl. 261—116)

1

This invention relates to apparatus for eliminating dust and fumes and more particularly to apparatus for collecting and carrying away dust and fumes from a casting shake-out space.

In co-pending application Serial No. 643,189, filed January 24, 1946, by Webster and Petty, there is disclosed and claimed a Method of and apparatus for collecting dust and fumes from a foundry shake-out space in which the dust and fumes are collected and carried away by parallel high velocity water streams. In apparatus of this type unless the water streams or jets are collected with a minimum of impact and splashing, mists tend to accumulate and to roll away from the point of collection of the water streams, carrying with them wetted dust particles and a certain amount of fumes. It is one of the objects of the present invention to provide an improved apparatus in which this condition is minimized or eliminated.

Another object is to provide apparatus in which any mist created around the jets is positively drawn away from the shake-out space.

Still another object is to provide apparatus in which spray and mist in the shake-out space is minimized.

The above and other objects and advantages of the invention will be more readily apparent from the following description when read in connection with the accompanying drawing, in which—

Figure 1 is a perspective view of an apparatus embodying the invention; and

Figure 2 is a diagrammatic end section.

In the form illustrated, the apparatus is adapted to be used on a foundry floor in that portion of the foundry where castings are shaken from the molds. As shown, a pit 10 is provided with a grate 11 through which sand shaken from the molds may pass to be collected and conducted away for reuse.

The apparatus comprises a pair of spaced parallel walls 12 and 13. The wall 12 is preferably higher than the wall 13 and the latter extends to the bottom of the pit 10 to separate it into a main portion underlying the casting shake-out area and a small back portion 14 for collecting water and entrained material. The walls 12 and 13 define a shake-out space which is open at the top and at both ends so that molds, as indicated at 15, can be carried into the space by cranes operating on a track 16 above the space. It will be understood that the usual shake-out table or other apparatus to assist in removing the cast-

2

ings from the molds may be provided in the shake-out space.

The wall 12 carries at its top a series of spaced parallel nozzles 17 connected to a header or manifold 18 for supplying water to the nozzles at a pressure on the order of one thousand pounds per square inch or more. The nozzles are arranged to direct spaced parallel water jets 19 across the top of the space and over the top of the wall 13, as shown. As explained in the co-pending Webster and Petty application, these jets create reversely rotating parallel vortices which draw dust and fumes into the jets so that they will be carried away from the shake-out space to be collected with the water from the jets.

A back wall 21 is spaced back of the wall 13 and extends above the wall 13 to terminate in a forwardly projecting portion 22. The wall 21 is preferably spaced above the screen or grating 11 to provide an air passage under it which communicates with the space between the back wall 21 and an end closure 23. Water from the jets together with dust fumes and air entrained thereby will pass downwardly between the walls 13 and 21, the water being collected in the pit section 14. The air together with lighter fumes will flow upwardly between the walls 21 and 23 and may be directed to any desired point of disposal.

In order to produce a positive circulation of air and gases including mist around the jets down between the walls 13 and 21, a curved baffle 24 is provided against which the jets are directed. As shown, the lower edge of the baffle lies substantially midway between the top of the wall 13 and the wall 21, and the baffle extends upward and forward to be spaced from the forwardly extending top 22 of the wall 21. The baffle is so placed that the jets 19 will strike it substantially tangentially and will be directed by the baffle down and between the walls 13 and 21. The air, dust and fumes entrained by the jets will be carried with the water to be conducted away from the shake-out space. Air and mist above the jets will be positively drawn into the space between the baffle 24 and the top wall portion 22 due to the injector action of the jets created by the baffle. Thus this mist which may carry with it some dust and fumes is positively drawn away from the shake-out space and is prevented from floating out into the foundry area.

To prevent the accumulation of mists adjacent the discharge tips of the nozzles, a second angular baffle 25 may be provided adjacent but spaced from the top portion of the wall 12 and

terminating in a horizontal part underlying and spaced from the jets. The action of the jets will produce a positive circulation around this baffle to withdraw from the shake-out space dust, air and fumes as well as any mist which may tend to accumulate adjacent the wall 12. While this baffle may be omitted, in many cases it assists in keeping the shake-out space free from undesirable fumes, dust and mist.

While one embodiment of the invention has been shown and described in detail herein, it will be understood that this is illustrated only and is not intended as a definition of the scope of the invention, reference being had for this purpose to the appended claims.

What is claimed is:

1. Apparatus for eliminating dust and fumes comprising first and second spaced parallel walls, a series of nozzles mounted adjacent the top of the first wall and spaced along the top edge of the first wall to direct a series of parallel high velocity water jets lying substantially in a plane over the space between the walls and over the top of the second wall, a back wall spaced back of and extending above the second wall, and a curved baffle lying between and spaced from the back wall and said second wall, the baffle extending above the other wall to receive the water jets and direct the water and entrained material down in the space between the second wall and the back wall and means providing a free outlet from the space between the second wall and the back wall for air entrained by the jets.

2. Apparatus for eliminating dust and fumes comprising first and second spaced parallel walls, a series of nozzles mounted adjacent the top of the first wall and spaced along the top edge of the first wall to direct a series of parallel high velocity water jets lying substantially in a plane over the space between the walls and over the top of the second wall, a back wall spaced back of and extending above the second wall, a curved baffle lying between and spaced from the back wall and the second wall, the baffle extending above the second wall to receive the water jets and direct the water and entrained material down in the space between the second wall and the back wall and means providing a free outlet from the space between the second wall and the back wall for air entrained by the jets, and a second baffle adjacent but spaced inward from the first wall and having a horizontal portion underlying the jets.

3. Apparatus for eliminating dust and fumes comprising first and second spaced parallel walls, a series of nozzles mounted adjacent the top of the first wall and spaced along the top edge of the

first wall to direct a series of parallel high velocity water jets lying substantially in a plane over the space between the walls and over the top of the second wall, a back wall spaced back of said second wall with its top projecting above the second wall and angling forward, and a vertically curved baffle spaced forward from the top portion of the back wall and terminating between the top part of the second wall and the back wall and means providing a free outlet from the space between the second wall and the back wall for air entrained by the jets.

4. Apparatus for eliminating dust and fumes comprising spaced parallel vertical walls, a series of nozzles mounted adjacent the top of one wall to direct a series of parallel high velocity water jets substantially in a horizontal plane over the space between the walls and over the top of the other wall, and a baffle having a vertical portion spaced inwardly from said one of the walls and having a horizontal portion underlying the jets in the space between said baffle and the other wall being unobstructed to provide free upward flow from the space between the walls to the jets.

5. Apparatus for eliminating dust and fumes from a casting knockout space or the like comprising spaced vertical parallel walls of different heights defining a space open at the top and at least one end, a series of nozzles mounted adjacent and spaced along the top of the higher wall to direct parallel high velocity water jets substantially in a horizontal plane across the top of the space and over the lower wall, a back wall spaced back of and extending above the lower wall, and a vertically curved baffle between and spaced from the lower wall and the back wall and curving forward above the lower wall to receive the jets and means providing a free outlet from the space between the lower wall and the back wall for air entrained by the jets.
